UNITED STATES PATENT OFFICE.

FRANK MCCLINTOCK, OF MOUNT VERNON, NEW YORK, ASSIGNOR TO THE
EMPIRE MACHINE CORPORATION, A CORPORATION OF NEW JERSEY.

MACHINE FOR JUSTIFYING TYPE.

SPECIFICATION forming part of Letters Patent No. 693,145, dated February 11, 1902.

Application filed July 20, 1900. Renewed December 14, 1901. Serial No. 85,939. (No model.)

To all whom it may concern:

Be it known that I, FRANK MCCLINTOCK, a citizen of the United States, and a resident of the city of Mount Vernon, in the county 5 of Westchester and State of New York, have invented a new and useful Improvement in Machines for Justifying Type, of which the following is a specification.

My invention relates to an improvement in 10 machines or apparatus for justifying and spacing out lines of type to a uniform length or measure, and particularly to that type of justifying-machine which is described and claimed in certain Letters Patent granted 15 upon my application, the first of which is numbered 608,002 and is dated July 26, 1898, and the second of which is numbered 635,866 and is dated October 31, 1899.

The invention will be best understood by 20 reference to the accompanying fourteen sheets of drawings, forming a part of this specification, in which—

Figure 1 is a plan view of the machine. Fig. 2 is a plan, partly in section, of the upper end 25 of the machine, showing the justifier about to operate. Fig. 3 is a plan view, partly in section, showing the justifier actually in operation. Fig. 4 is a rear elevation of the machine indicated by line A A in Fig. 1. Fig. 5 is a side view of the machine, showing the 30 device for actuating the line-holder indicated by line B B in Fig. 1. Fig. 6 is a detailed view of parts of the mechanism for actuating the line-holder indicated by the line C C in Fig. 5. Fig. 7 is a cross-section on the 35 lines D D of Figs. 1, 2, and 3, showing the cams, wedge-hook, and space-rack in an advanced position. Fig. 8 is a plan view of particular mechanism shown in Fig. 7. Fig. 9 is a vertical cross-section on the lines E E of 40 Figs. 1 and 2, showing the clutch for throwing the justifying mechanism into gear. Fig. 10 is a vertical cross-section on the lines D D, Figs. 1, 2, and 3, showing the cams and the 45 wedge-hook and the space-rack about to operate. Fig. 11 is a front elevation of the entire machine indicated by line F F in Fig. 1. Fig. 12 is a vertical longitudinal section on the lines G G, Figs. 1 and 4. Fig. 13 is a 50 cross-section of the space-bar-inserting mechanism on the lines H H of Fig. 1. Figs. 14,

15, and 16 are detailed views of the space-bar-elevating mechanism. Fig. 14 is a section on the line I I of Fig. 15, and Fig. 15 is a section on the line J J of Fig. 14. Fig. 16 55 shows the pivoted support for the space-bar before the space-bar is driven into the line-holder. Figs. 17, 18, 19, 20, and 21 are enlarged detailed views of the line-holder and the space-bar, Fig. 20 being a section on the line K K. Fig. 22 is a plan view of the particular parts of the machine which effect the justification proper, and Fig. 23 is a vertical cross-section of the same parts on the line L L of Fig. 22. 60

Similar letters and numerals refer to similar parts throughout the several views.

The following is a general description of the machine.

The following elements found in this machine are common to all justifying-machines of the present type.

c is a sliding line-holder in which the type are assembled and in which justification is effected.

f is a vertical plate against which the line-holder slides and which forms its inner face.

y is a slot on the inner face of the plate f opposite the line-holder c, arranged to receive the extremities of the space-bars as they are 80 inserted therein.

a is the main table of the machine; h, the outer supporting-frame, which serves also as a bearing for the driving-shaft t; s, the type-chute through which the type enters the line-holder c.

b and d are two parallel channels in which the line-holders travel downward and upward, respectively. The former is formed on the upper face of the plate a and the latter 90 by the plate 819.

e is the series of space-bars.

The plate f contains a groove g, through which the hooked slide travels which drives the line-holders.

m is the raceway, formed in the plate a, in which the space-bars e are returned from the lower to the upper end of the machine. i is the plate which covers the same.

j is the channel in which the spring which 100 returns the space-bars rotates.

l is the space-holder.

n is the main bed-plate of the entire machine.

p is the key which actuates the space-bar-driving mechanism.

t is the main driving-shaft; *w*, the justifying-shaft; *o*, the sleeve upon the justifying-shaft by means of which the justifying mechanism actuated by it is connected with it.

q is the driving-pulley.

r is the end plate of the machine; *k*, the key which actuates the line-holder-advancing mechanism; *u*, the galley on which the justified lines of type are assembled.

2 represents the assembled line in the line-holder.

The line-holder and space-bars.—Two line-holders *c c* are provided with each machine, which are really composing-sticks having the capacity for a single line of type and the necessary temporary spacing devices. The line-holders are of the shape shown in Figs. 17 to 21, inclusive.

12 is the type-recess cut on the face of the line-holder, which is of a width and depth to correspond with the size of type used and extends the entire length of the line-holder. It is closed at the front end by a fixed stop 2 and at the rear end by a movable block 6. A longitudinal opening or slot 1 is provided extending almost the entire length of the line-holder.

The block 6 is adapted to be moved longitudinally along the recess and to be securely clamped to the rear wall of the line-holder at any desired point by means of the screws 5, Figs. 18 and 21. The line-holder contains in its interior a curved rib 10 for the purposes hereinafter described. The movable block 6 is provided with a spring-plate 8, which may either be pivoted at one end or

40 side of the block 6 at the point 9 and held normally in the position shown in Figs. 17 and 18 by means of a spring 21, encircling the sliding pin 7, or else it may be supported upon pins 7 7, sliding in suitable openings

45 in the block 6 and held normally in the position shown in Figs. 20 and 21 by means of the spring 21. The object of making the plate 8 movable is to enable it to be moved at the proper instant out of the path of the

50 cam 3, which is constantly rotating upon the shaft 60 and serves to throw the type forward in the recess 12 as fast as it is assembled therein. In order to draw in the plate 8 and permit it to pass the cam as the line-holder moves down its track, a beveled plate 22 is provided, (shown in Fig. 3,) attached to the edge of the side plate *f*, which as the line-holder moves down the groove *b*, in which it travels, engages with the face of the plate 8

55 and pushes it back a sufficient distance to enable it to pass the cam 3, and when it has passed by the cam the spring 21 thereupon throws the plate 8 out to its original position, and thus closes the end of the recess 12, as before. The space-bars 44 are shown in detail in Fig. 19. They are provided at their upper rear ends with a hook 20, as shown.

The tapering portion of the space-bars 44 varies in thickness from somewhat less than the thinnest space-blank which it is desired to use up to the thickest. The lower edge 19 of each of the space-bars from the point 17 to the point 18 is cut away for a sufficient distance to make the height of the space-bar such that it will clear the rib 10 in the line-holder and will move freely longitudinally through the opening 1 therein. Between the points 17 and 23 at the point 15 the lower edge is curved, so that the height of the space-bar, while slightly less than its full height, is somewhat more than the distance between the rib 10 and the lower edge of the top of the slot 24. The longitudinal slot 14 in the space-bars allows them to be compressed while passing the rib 10, and the notch 15 is so located that when the space-bar is first inserted into the line as a temporary space the notch 15 will rest on the rib 10, and the spring of the two parts of the space-bars separated by the slot 14 will serve to hold it securely in place. It will be evident that this construction will allow of the space-bars being readily driven farther through the line and will also prevent them from being accidentally withdrawn therefrom. The distances on the space-bars represented by the different thicknesses of spaces used is indicated by *xx* in Fig. 19.

Upon the top plate *a* rests a plate 70, carrying on its outer face a series of bristles 73, the ends of which engage with the outer ends of the space-bars, and thus prevent them from shifting their normal position at right angles to the line of type in the line-holder after insertion therein. This plate is adjustable on the top plate by means of set-screws 72, passing through the slots 71 in the plate.

The type-advancing cam.—The type is kept constantly advanced in the line-holder as it is assembled by means of a rotating cam 3. This cam is placed at the end of a shaft 60, passing through a suitable bearing in the upper part of the plate 68, as shown in Figs. 2 and 5, which carries at its extremity a small pinion 61, the teeth of which are arranged to mesh into the teeth of an idler 62, rotating on the shaft 64 on the plate 65. This idler engages in turn with a gear 63 at the extremity of the main driving-shaft *t*. The relations of the parts are such that the speed of the shaft 60 will be very much increased and the cam will rotate continuously and very rapidly. The shape of the cam is such that as it comes in contact with the types assembled in the line-holder it will throw them and the space-bars forward and cause them to be set up in a homogeneous line. The plate 68 is pivoted in the side plate *f*, as shown in Fig. 2, in such a manner that the top part, in which the cam-shaft 60 has its bearings, may be moved to and fro a short distance in order that the cam may be adjusted properly to the position of the type-chute *s*. The set-screws 66, which pass through the lugs of the plate 68, which is secured to the side plate *f*, and

impinge on either side of the plate 65, serve to adjust it accurately and then to retain it rigidly in such position.

The space-bar-inserting mechanism.—Instead of ordinary space-blanks tapering or wedge-shaped space-bars are employed, which, as in other machines of the character of the present machine, are inserted temporarily crosswise through the line between the words as composition proceeds or as the type is transferred to the line-holder and which are replaced mechanically by ordinary space-blanks, as will be fully described hereinafter. A series of these space-bars is shown, (designated as *e*.) and the individual bars composing the series are designated by 44. The position of the bars prior to insertion will be best seen by reference to Fig. 2, in which the series is shown assembled at the upper end of an inclined raceway *m*, held in position by a spiral spring-coil 905, rotating in a groove *j*, the effect of which will be referred to hereinafter. From the position shown at the top of the raceway *m* in Fig. 2 the space-bars are raised one by one when they are to be inserted, and as fast as they are raised they are pushed forward into the line-holder at the proper point.

The inserting mechanism consists of two parts—first, an elevating mechanism for lifting each single space-bar from the storage-channel at the head of the raceway up to the level of the line-holder, and, second, a space-bar-inserting rod which forces the space-bar forward into the line-holder after it has been thus elevated. These features will be best explained by reference to Figs. 4 and 10, taken in connection with the detail views, Figs. 14, 15, and 16.

(a) The elevating mechanism: In the detail views, 44 represents, as before, the foremost of the series of space-bars shown in the raceway held in position by the spiral spring 905, the raceway being formed between the main plate *a* and the cap-plate *i*, both of which are inclined at the appropriate angle at which the machine works. 100 is the space-bar-elevating plate, which is arranged to slide vertically in the end plate *r* of the machine. This is attached to a vertical plate 101, arranged to slide in suitable ways 102, cut in the inner face of the plate *r*. The extremity of the plate 101 is pivoted to a lever 103 by the screw 104. A spring 105 is provided, attached at the upper end to the pin 106, upon the outer face of the end plate *r* and at the lower end to the pin 107 upon the face of the sliding plate 101, which is in turn attached to the plate 100.

(b) The inserting mechanism: The space-bar-inserting mechanism will be best seen by reference to Figs. 3 and 4. It consists of a sliding plate 110, attached to a rod 109 and sliding in a groove in the upper surface of the end plate *r*, attached at its outer end by pin 111 to the long arm 112 of a bent lever, which lever is pivoted at the point 113 to the

frame *h* and is provided with a short arm 114, carrying a loosely-rotating roller 115. A spring 125 is provided, attached at one end to the pin 126 upon the long arm 112 of the lever and at the other end to a pin 127 on the outer surface of the end plate *r* of the machine.

The space-bar-inserting mechanism and the space-bar elevator are both actuated from the driving-shaft *t* by means of suitable cams. (Shown in detail in Figs. 2, 4, 8, and 12.) The driving-shaft *t* rotates in suitable bearings 39 and 40 in the plate *f* and the frame *h*, respectively, and is driven from any convenient source of power. It carries a collar 117, which is attached to it by the pin 116 and which rotates with it. Upon the shaft *t* is a loose sleeve 119, carrying at one end a cam 118, the outline of which is shown by the dotted line in Fig. 13. The roller 115 engages with the periphery of this cam and is kept in contact with it by the spring 125, so that the lever 112 is actuated by the rotation of the cam 118. Attached to the other end of the sleeve 119 is a second roller 120. The roller 120 is provided with an interior cam-groove 128, cut on its face, as shown in Figs. 4 and 13, within or along which rotates a roller 122, rotating on a pin attached to the lower end of the arm 121, which is in turn attached by the screws 124 to the lever 103, which actuates the plate 100, and it will thus be apparent that as the cam 120 rotates the cam-groove 128 will cause the roller 122 to move and the lever 103 to rise and the spring 105 to be retracted. The form of the cams 128 and 118 and their position on the sleeve are such that as the shaft *t* rotates they will be so timed with reference to each other that the cam 118 will first cause the space-bar-elevating mechanism to raise the foremost space-bar and then draw down the lever 103 to its normal position, and after the proper interval of time has elapsed the cam 118, by reason of its form, will begin to operate upon the roller 115, and thus cause the forked lever 121 to be drawn in by the spring 125, and the space-bar-inserting rod 110 will push the space-bar which has just been raised in place into its place in the line-holder.

In order to throw the mechanism in and out of gear, a ratchet-wheel 129, the teeth of which are of the shape shown at 131, is provided, keyed to the rotating shaft *t* in close proximity to the outer surface of the cam 120. The face of the cam 120 carries a pivoted dog 132, attached at the point 133, provided with a spring 135, which causes the dog to be normally thrown forward and the tooth 134 to engage with the teeth 131 of the wheel 129. The tail of the dog 136 is engaged to be tripped by the tooth 137 on the end of a rocking lever 138, pivoted to the arm 139 on the bed-plate *n* at the point 149 and to be held normally thrown forward at its lower end 140 by means of the spring 141. The lower end of the rocking lever 140 is actuated by means of

a wire 142, connected with a suitable key-lever *p*, Fig. 5, so that when the key-lever is actuated the lower end of the rocking arm is drawn in, the spring 141 is compressed, the 5 tooth 137 is disengaged from the tail 136 of the dog, and the dog 132 is thrown forward, whereupon the tooth 134 of the dog engages with one of the teeth 131 of the ratchet 129, thus causing the disk 120 and the cam 118 on the 10 sleeve to rotate with the shaft *t* throughout a complete revolution. Upon the release of the key the hooked lever 138 is returned to its normal position by means of the spring 141. As the cam 120 completes its revolution the 15 tail 136 of the dog 132 engages the hook 137 on the lever 138, which withdraws the tooth 134 of the dog 132 from its engagement with the ratchet-tooth 131, and the cam will cease to rotate. In order to prevent the clattering 20 of the dog 132, which would occur if the cam 120 were not kept from rotating backward, a brake-shoe 143 is provided, engaging with the periphery of the cam, pivoted at 144 to a bearing 145, attached by the screw 146 to the plate 25 *n* and held against the periphery of the cam by the spring 147.

It is essential that the movement of the front end of a space-bar in entering the line of type shall be so timed that it will not strike 30 either the cam 3 or the last type set in the line-holder. It is necessary, therefore, to so time the revolution of the cams 118 and 120 with respect to that of the cam 3 that whenever a space-bar is inserted into the line the 35 cam 3 will be in the position shown in Figs. 2 and 17, allowing the thin end of the space-bar to be inserted into the line of type between the hub of the cam and the last type set in the line-holder. This is effected by 40 means of the gear-wheels 61 and 63, which are connected by means of the idler 62 in connection with the teeth 131 on the ratchet-wheel 129. These are so proportioned that the revolution of the main shaft *t* and of the 45 ratchet-wheel 129 throughout a distance equal to the pitch of the teeth 131 will cause one revolution of the cam-shaft 60. In other words, one complete revolution of the main shaft *t* will cause the cam-shaft 61 to make as 50 many complete revolutions as there are teeth on the ratchet-wheel 129. In the machine shown the cam-shaft is geared to make seven revolutions to each revolution of the main shaft *t*, and the cam 3 is secured to its shaft 61 in such a position that the entering point 55 of a space-bar will always find it in the position shown in Figs. 2 and 17, whichever one of the teeth 131 of the ratchet-wheel 129 may be engaged by the dog 132.

60 For the purpose of adjusting the space-bar elevating and driving mechanism with respect to the cam 3 the rear or upper end of the top plate *a* is cut away, as shown in Figs. 2 and 15, and an adjustable angular end plate 65 275 is provided having the slots 276 and screwed to the bed-plate by the screws 277 passing through the slots. By loosening the

screws the plate may be shifted up and down, carrying with it the driving and elevating mechanism.

In order to hold each space-bar in the elevated position while the space-bar-inserting mechanism is acting upon it, a pivoted plate 267 is provided. (Shown in Figs. 14, 15, and 16.) This is pivoted at the lower end at either side by the pivots 261 to a plate 263, which latter plate is attached to a cap 264 by means of the screws 265. The cap-plate 264 is attached to the upper end of the plate *r* by the screws 266 and is slotted throughout its width up to a certain point, there terminating in a shoulder 268, as shown in Fig. 15, arranged to engage with the lug or hook 20 on the end of the space-bar in order to limit the forward movement of the latter.

The plate 267 is normally held in a forward position by means of a spring 262, which forces it constantly forward. When the foremost space-bar in the line is raised by the elevating-plate 100, the plate 267 is forced back against the spring 262, and the plate 100 passes by the plate 267 and holds the space-bar in the position shown by the dotted lines in Fig. 14 for an instant. The instant that it begins to return the spring 262 forces the 95 plate 267 outward and under the space-bar and holds it there while the space-bar-driving mechanism operates on it.

The adjustable plate 275 is beveled, as shown by the dotted line 278 in Fig. 14 and the shaded surface in Fig. 15. This enables the line-holder *c* in rising to move forward a sufficient distance for the front line-stop 2 in the line-holder to clear the cam 3.

The line-holder friction-brake.—During the 105 composition of a line some sort of device is necessary which will hold the line-holder *c* to a certain extent and prevent it moving too rapidly down the track or way while the types and space-bars are being assembled therein. 110 The form of device employed for this purpose is shown in Figs. 3 and 12. This consists of a vertical plate 50, slightly beveled at the rear end 51, as shown, of such dimensions as to fit into the channel 25 on the side of the line-holder traveling on the track *b*, cut on the face of the cap-plate. The plate 50 is fastened to the extremity of a sliding rod 53, which is arranged to slide in a suitable opening or seat 54, cut longitudinally through the cap-plate, the movement of which is limited by a pin 55 passing through a slot 56 in the rod 53. The outer end of the rod impinges against a coil-spring 57, placed in the continuation of the channel 54, the outer end of which 115 abuts against a thumb-screw 58, mounted upon a screw-pin 59, which screws into an appropriate threaded surface cut on the inner face of the channel 54, so that by turning the thumb-screw the spring 57 will be compressed 120 and the plate 50 will be forced forward against the line-holder with an appropriate degree of pressure. By means of the beveled extremity 125 51 the groove 25 on the side of the line-holder

as it descends will always be forced into connection with the plate 50, and the friction between the line-holder *c* and the plate 50 will serve to hold the former during the operation 5 of filling and prevent it from advancing too rapidly.

Line-holder-advancing mechanism.—For the purpose of advancing the line-holder, after it has been filled and the space-bars inserted 10 therein, to the space-inserting mechanism and thence to the galley, where the justified line is discharged, mechanism is provided which is shown in detail in Figs. 1, 2, 3, 4, 5, and 6.

For the purpose of carrying the line-holder 15 *c* and permitting it to travel forward an inclined track or way *b* is provided, formed upon the top of the plate *a* by the inner edge of the cap-plate *i*, as shown in Fig. 23 in cross-section. The inner surface of the plate 20 *f* contains a groove *g*, running its entire length. The form of this groove will be more particularly shown in Figs. 6, 7, 8, and 9.

In the groove *g* is a slide 159, which contains a recess 160 at its rear end, as shown in 25 Fig. 2. This recess contains a pivoted hook 161, pivoted at the point 162 and the longer end of which is prevented from extending too far out into the channel in which the line-holder travels by means of the extended end 30 163. The hook is normally thrown outward by means of a spring 164, but when the slide is retracted the face of the hook 161, coming in contact with the end of the line-holder, compresses the spring 164, and thus passes by the 35 line-holder, and after its passage is thrown forward to its original position and thereupon engages with the rear end of the line-holder *c*. It will be obvious that when the slide 159 is again moved the hook 161, attached thereto, impinges against the rear end of the line-holder and causes the same to be moved forward. In order to actuate the slide 159, a pin 40 166 is provided, passing through the slot 165, the length of which is shown in Fig. 2 and the precise position of which is shown in Figs. 45 5, 7, 9, and 10. Through this slot passes the pin 166, which is attached to the slide 159 and to either side of which are attached two cords 167 and 168, respectively. The cord 167, as 50 will be seen by Fig. 5, passes over a grooved pulley 169 at the point shown at the lower end of the side plate *f*, and thence passes over a horizontal grooved pulley 170, placed at a convenient point, thence over another vertical 55 pulley 171, arranged in an equally appropriate position, and terminates in a weight 172, to which it is attached by a ring 173, formed at the top of the weight. On top of the weight 172 is placed a loose weight 174, containing an opening in its center 175, through which the cord 167 passes, and a bracket 176, provided with a ring 177, is so arranged with reference to the weights that when the weight 172 falls it will pass through the opening in the ring 177. 60 The weight 174 is of greater diameter than the ring, so that when it falls with the weight 172 it will be held upon the ring 177, attached

to the bracket 176, and will theretupon cease to add its weight to that of the weight 172. It will be observed that the effect of the 70 weights 174 and 172 upon the cord 167 is to normally draw the pin 166 downward and with it the slide 159.

The upper cord 168 passes over a grooved pulley 178, mounted on the shaft 179, and is 75 attached thereto rigidly at the point 180. To the face of the pulley 178 is attached the cam-pulley 181, grooved on its periphery, as shown in Figs. 1 and 5. To the point of the cam 181 at the point 182 is attached a cord or chain 80 183, passing over a grooved loose roller 184, connected at its lower extremity with the cross-head 185, attached to the piston-rod 186 of a compressed-air cylinder 187. The rod 186 is attached to the piston 188, sliding in 85 the hollow chamber 189 of the cylinder 187, and it will be obvious that as long as the chamber 189 is filled with compressed air the piston will assume the position shown in Fig. 6 and the cross-head 185 the position shown 90 in Fig. 5, as well as in Fig. 6. Compressed air is supplied to the chamber 189 from a pipe 191, connected with any convenient source of supply, through a port 192. This port is opened and shut by means of the sliding valve 95 193, controlled by a spring 194, which sliding valve contains in its interior an outlet-port 195, so that when the valve 193 is in the position shown in Fig. 6 the chamber 189 is constantly kept full of compressed air; but when the valve 193 is slid upward the port 192 will be closed and connection will be made through the air-port 195 with the interior of the chamber 189, and the compressed air in the chamber 189 will flow out through the port 195 into 100 the air, and the piston 188 can then be retracted by the effect of the weights 172 and 174. For the purpose of opening the valve 193 to allow the escape of the compressed air a key *k* is provided, pivoted to the side plate 105 *f* at the point 196. This lever is composed of two arms 197 and 198, to the longer of which is attached a finger-piece 199 and to the upper of which is attached cord 200 at the point 201. The other extremity of the cord 200 is 110 attached to a lever 202, pivoted to a shaft 203, held upon bearing 204. The other extremity of the shaft carries a similar lever 205, set at an appropriate angle, which is pivoted to the extremity of the sliding valve 115 193 at the point 206. When, therefore, the finger of the operator is pressed upon the finger-piece 199 of the key *k*, the cord 200 is retracted and the valve is opened. A spring-catch 207 is provided, pivoted at the 120 point 208 to the side plate *f*, arranged to engage with a stud 209 upon the shorter end 198 of the key *k*. When the key *k* is depressed, the hooked end of the lever 207 is forced downward by the spring 210, engages 125 with the stud 209, and holds the valve open. For the purpose of closing and releasing the device automatically the pin 166, when it reaches the lower end of its line of travel,

trips the outer end 211 of the lever 207, extends the spring 210, and raises the hooked end free of the stud 209 upon the lever 198, whereupon the spring 194 will close the valve 193 to the air and permit the compressed air to enter again through the port 192, thus filling up the chamber 189, driving down the piston 188, drawing down the cord 183 by means of the cross end 185, and causing the slide 159, by means of the cord 168 and intermediate cam mechanism, to be raised to its original position. When the key *k* is actuated and the air passes out of the cylinder 187, at that instant the slide is moved downward by the force of the weights 172 and 174 acting upon the cord 167. During the earlier part of the line of travel a certain amount of friction is necessarily exerted upon the line-holder by means of the plate 50, as above described, and hence a heavier weight is necessary during the first part of its travel than is necessary or desirable after it has passed down to the justifying mechanism and is no longer in contact with this plate. Hence the position of the weights 172 and 174 with reference to the ring 177 is so timed that the instant the line-holder is released from the friction-plate 50 the weight 174 will come in contact with the ring 177, and the cord 167 will thereupon be relieved of its weight and will be carried down by the force of the weight 172 only to the end of its line of travel. When the cylinder 187 is being filled with compressed air, the weight 172 will be raised until it passes up through the ring 177, and thereupon it will carry with it and raise the weight 174, and when the position of the cross-head 185 (shown in Fig. 5) is attained the weights 174 and 172 will assume their original position, as is shown in this figure. In order to facilitate the raising of both weights without unduly lengthening the stroke of the piston 187, the cam 181 is given an increasing diameter proportionate to the increased weight, so that as the weight increases the radius of the cam increases, and thus the same effect is accomplished as would be by making the stroke of the compressed-air piston longer.

It will be evident that other mechanical means than the compressed-air cylinder shown may be employed to draw up the slide 159 and weights 172 and 174 to their operative position without departing from the principle of my invention.

The line-holder-holding mechanism.—The object of this is to hold the line-holder while the justifying-slide is operating. This will be best shown by reference to Figs. 1, 3, 7, 8, and 8. It consists of a slide 600, arranged to slide in suitable guides 601 upon the bed-plate *a*. The inner end of this slide carries a block 602, to which is attached a slide 609, the inner end of which is arranged to impinge against the outer face of the line-holder, as shown in Fig. 7. The slide 600 is normally forced forward and held against the line-

holder by means of a spring 603, placed underneath the slide and between it and the bed-plate, one end of which spring is attached to the slide at the point 604 and the other end of which is attached to the bed-plate at the point 605. The slide is retracted by means of mechanism attached to and operating with the sleeve *o*. This mechanism consists of a cam 606, keyed to the sleeve *o*, which cam engages with a roller 607 at the extremity of a bracket 608, attached to the slide 600. When the sleeve *o* is at rest, the slide is held in the position shown in Figs. 2 and 10. The position of the cam 606 on the sleeve *o* is such that after the operation of removing the space-bar and inserting a space-blank in lieu thereof is completed the raised part of the cam 606 again engages the roller 607, thereby withdrawing the end of the slide 609 from contact with the line-holder, which is then free to move along its track until another space-bar, by engaging the stop 375 and the end face of the slot 13, brings it to rest.

The space-bar-driving and space-selecting mechanism.—By this title is designated that particular mechanism which arrests the movement of the line-holder and then drives the space-bars farther through the line, thereby increasing the spacing between the words until the line has been expanded to the limit of the line-holder, and withdraws the space-bars one by one, inserting at the same time in lieu thereof space-blanks of such individual and aggregate thickness as will accurately and properly justify and space out the line. The principle of the present machine differs materially from that of former machines of the same general character in that instead of using two independent mechanisms, one for driving in all of the space-bars simultaneously and a second one for afterward driving them in successively for the purpose of apportioning the fractional excess of spacing, the same result is accomplished by a single mechanism operating intermittently, whereby the line is progressively expanded to the limit of the line-holder.

In order to understand the difference in principle between the mechanism employed in the present machine and that employed in the earlier machines, attention must be called to the conditions shown in Figs. 2, 3, and 22. These figures show a line-holder containing a line of type set up in the appropriate channel in the line-holder, with seven tapering space-bars inserted therein between the separate words. Heretofore when permanent or temporary spaces have been used in connection with automatic mechanism for justifying and spacing ordinary movable type it has been thought necessary to provide a primary bunter extending along the entire length of the line, which may be driven or forced against the thick ends of all the tapering devices in the line, thereby driving them simultaneously farther through the line until the increased spacing thus formed between the types con-

tiguous thereto expands the line to its full length as limited by the stops in the line-holder. This uniform driving in of all the space-bars results in uniform spacing between 5 all of the words in each line and is especially adapted to that class of machines called "lino-type-machines," where a line of matrices and expanding-spaces are assembled and justified by causing the expanding-spaces to spread 10 the line to its limit in the line-holder and from which a slug or solid line of type is cast, after which the matrices and spaces are at once distributed by suitable means. It is evident that in such machines the spacing devices used 15 are essentially permanent spaces, corresponding in function with the space-blanks used with ordinary movable types. In using tapering or wedge-shaped spacing devices in machines for justifying or spacing ordinary movable types, wherein space-blanks of the usual 20 construction must be substituted therefor in the finished line, it will very rarely happen that any one of the space-blanks provided will be of exactly the thickness required to fill the 25 opening between the types left by the withdrawal of the temporary spacing device, and hence it will become necessary to use a space-blank of less thickness. From this will result that there will be a looseness of the line 30 by some fraction of the difference in thickness between the successive space-blanks, which looseness will have continued throughout the line and result in a very serious shortening of its length in accordance with the number 35 of such thin spaces which are used. It was necessary heretofore whenever this fractional deficiency had accumulated to a total amount equal to the unit of difference between two successive space-blanks that provision be 40 made for inserting the space-blank of the next greater thickness. This has been heretofore accomplished by providing a second bunter, which again drove in one or more of the spacing devices remaining, after the insertion of 45 each successive space-blank, farther through the line, so as to again expand the line to its full length. None of these secondary bunters heretofore used have been satisfactory in practice, for the reason that the inherent 50 method of operation of the machine caused such thicker spaces as were required in most lines to be generally grouped together either at the beginning or at the end of the line, which produced an unsatisfactory result. It 55 will be obvious that in the justification of type it is extremely desirable that in lines where spaces of different thicknesses are used they should alternate uniformly with the thinner spaces throughout the line. Very rarely 60 when a line of type is assembled of the character of that shown in Fig. 2 is the line completely filled out, but a space is usually left, as shown by 300 in Fig. 22, and when the line-holder begins to travel down its track this 65 space will always be at the upper end of the line. When, however, the foremost space-bar in the line-holder comes in contact with

the stop 375 and face of the slot 13, the effect of the weight 172, acting on the cord 167, is to cause the line-holder to move downward, 70 and thereby shift the entire line of type with reference to the line-holder up in the type-channel back against the line-stop 8. The type composing the word in front of the foremost space-bar by reason of the angular position of the line-holder remains in the same position in the forward end of the line-holder; but the rest of the line having been shifted the space which was formerly at the upper end of the line-holder when the line-holder 80 began to travel will now be found at the lower end in front of the foremost space-bar, as is shown in Fig. 22.

It will be observed that where in a line-holder of this character the space-bars are 85 driven in either successively or collectively from time to time for removal the effect of the driving on these space-bars is to expand the line and will therefore tend to throw the entire line-holder back against the pressure 90 exerted on hooked slide 159 by the weight 172.

In the line-holder shown in Fig. 22 seven space-bars are shown. Let us assume that a fixed space-bar driver substantially parallel to the line-holder impinges against these to 95 drive them in with a force, say, equal to seven pounds. When it strikes against all seven of the space-bars, it impinges against each with a theoretical force of, say, one pound. As each successive space-bar is withdrawn 100 the same amount of force is exerted against the remaining space-bars, and the consequence will be that when the end of the line is reached and the last space-bar is acted upon by the bunter this space-bar is subject to as much 105 force as all the space-bars were originally subjected to as the operations of justifying began. The result of such a condition is that the space-bars will be gradually driven 110 farther into the line toward the end of the line, and as a result the space-blanks substituted therefor will be proportionately increased, thus making an irregularly-justified 115 line. I have discovered that in a line-holder of the character of that shown controlled by 120 the forces above indicated, which tend constantly to keep the excess space which is to be filled with a space-blank upon the removal of the space-bar at the front of what is for the time being the foremost space-bar in the 125 line, a single bunter of substantially the construction shown will drive in the space-bars in such a manner as to give uniform spacing under varying conditions. This improved bunter does not drive in all of the space-bars 130 simultaneously, as has been done heretofore, but instead drives them in their final position one after the other progressively, only the foremost one being driven in its full distance each time the space-bar driver is made 135 to act. By thus combining the primary space-bar driver and the secondary space-bar driver into one and by combining with the secondary driver the adjustable spring devices which

relieve the pressure to be exerted upon the space-bars other than the foremost bar proportionately to the number of space-bars left in the line at any given time I find that I am able to effect a justification and spacing of the line which is uniform and accurate without requiring modification or adjustment for lines of different length.

- (a) *The space-bar-driving mechanism.*—
- 10 This will be more particularly seen by reference to Figs. 1, 2, 3, 7, 9, 10, and 12. In all machines of this class heretofore invented before the line-holder with its types and spacing devices have been acted upon by 15 mechanism which automatically withdraws the space-bars and substitutes therefor space-blanks of the proper thickness it has been considered essential to drive in all of the space-bars simultaneously as far as they 20 would go through the line until the increased spacing thereby formed by the thicker section of the space-bars between the types expanded the line to the full limit of the line-holder. In the present machine, however, 25 this method has been departed from in the interest of efficiency and simplicity, and the line-holder is caused to move in the first instance directly to the position where the first space-bar set in the line-holder will engage 30 with and actuate the trip which serves to throw the automatic justifying mechanism into gear. The space-bar-driving mechanism consists, primarily, of three parts, all of which are carried upon sliding justifying-bar 312. The first of these parts consists of a 35 plate 313, having its front parallel to the line-holder *c* and rigidly attached to the slide 312 by the screws 314. The second of these parts consists of a plate 315, pivoted to the plate 313 by the screw 316 and provided along its 40 front face with a series of teeth 317. The plate 315 is normally held in a position substantially parallel with the front face of the plate 313 by means of a sliding pin 318, sliding in a suitable seat upon a plate 319 and 45 constantly thrown forward by a spring 320. This plate may be adjusted with reference to the plate 313 by means of a screw 321, passing through a slot 322 in the plate 319. The 50 normal position of the plate 313 will be best seen by reference to Fig. 2. In order to limit the forward-and-backward movement of the plate 315, a slot 323 is provided in the plate, through which passes a screw 324 55 into the plate 313. For the purposes of driving in the foremost space-bar such a distance as will properly apportion the excess spacing required in most lines and then extracting the same the third element of the 60 construction above referred to is employed. This consists of a vertical plate 325, rigidly attached to the justifying-slide 312 at the side by means of the screws 326, as shown in Figs. 7 and 10. On the top of the plate 325 is a bar 65 327, pivoted to the plate at the point 328 and so arranged with reference to the plate 325 that it is normally held firmly against the

plate by means of the pressure exerted by a spring 329 on its rear end. The forward end of the plate 327 carries a hook 330, which is 70 arranged to engage with and pass over the hook 20 on the extremity of the space-bar 44 and as it returns to withdraw the space-bar 44 from the line-holder *c*, which is thereupon removed by the mechanism now to be described. 75

In order to distribute as nearly as possible the excess fractional spacing throughout the entire line at all points at which a space is to be inserted into the line, the plate 325 is so 80 constructed as to extend a slight distance in front of the front face of the plate 313, with the result that it will produce the results hereinafter to be described.

In order to actuate the justifying-slide 312, 85 a weight 331, attached to a cord 334, passing over a grooved pulley 335 and attached to a pin 336 on the slide 312, is provided, the effect of which is to keep the slide normally in an advanced position. A roller 337, carried upon a bracket 338, attached to the slide 312, is provided, which is adapted to engage with the face of an irregular cam 339, attached to the loose collar or sleeve *o* upon the main justifier-shaft *w*, the revolution of which cam by 95 reason of the curvature of its periphery allows the roller 337 and the slide 312 to move forward at the proper time through the action of the weight 331. In order to effect an engagement at the proper time between the shaft *w*, 100 which constantly rotates, and the sleeve *o*, carrying the cam 339, a trip mechanism (shown in Figs. 2 and 9) is provided. This consists of a rock-shaft arranged to rotate on a bearing 342 on a bracket 343, attached to the bed-plate, and the bearing 344 in the side plate *f*, and which performs various other functions 105 hereinafter referred to. The rock-shaft 341 terminates at its outer end in a bent arm 345, the lower extremity of which is provided with 110 a projection 346.

The shaft *w* carries, as shown in Figs. 2 and 9, a disk 348, which rotates with it in the direction shown by the arrow in Fig. 9, which disk is provided with a series of cog-teeth 349. 115 Surrounding the cog-wheel 348 is an annular disk 350, which by means of a long sleeve *o* carries two cams, among them the cam 339. A toothed dog 352 is pivoted at 353 in a seat cut in the thinner face of the ring 350, as 120 shown in Fig. 9, and the spring 354 tends to hold the tooth of the dog normally in engagement with the cog-teeth 349 upon the cog-wheel 348. The outer end 346 of the rod 345 rests normally under the lever 347 and holds 125 the dog back from the teeth, thereby compressing the spring 354 in the manner shown in Fig. 9 until such time as the shaft 345 is moved by appropriate mechanism. In order to move the rod 345 at the right time, the hanging rod 355 is provided at the inner end of the rod 341, which descends into a recess in the side plate *f*, which recess contains a slide 130 356, which projects out into the slot 13 in the

plate *f*, as shown in Figs. 2 and 3, and is normally held in the position shown in Fig. 2 by means of the spring 359 until such time as the extremity of the foremost space-bar in 5 the line-holder *c* comes in contact with it and forces in the slide, thereby contracting the spring 359 and causing the rod 355 to swing forward, thereby rotating the rock-shaft 341 and releasing the dog. Thereupon the dog 10 immediately engages with the teeth of the cog-wheel 348, and the disk 350, carrying with it the cam 339, is rotated. As soon as the foremost space-bar is withdrawn from the line-holder by the space-bar-withdrawing mechanism 15 the spring 351 causes the slide 356 to resume its original position, thus again tilting the rod 355 and releasing the dog, thereby causing the disk 350 and the cam 339 to cease rotating.

20 (b) *The space-selecting mechanism.*—The space-selecting mechanism is best shown in Figs. 1, 5, 7, 9, and 10. In the drawings, *i* represents a swinging space-rack containing a number of channels 500 for spaces of 25 different sizes, which is fitted in two ways 501 on an arm 502, pivoted at the point 503 to the side plate *f* of the machine. The space-blanks are of the ordinary construction, such as are used with movable types, and vary in 30 thickness by any convenient unit, the thinnest one in the right-hand compartment being of the same thickness as the space-bars at the point where they are first inserted into the lines of type. Since the taper of the space-bars is uniform, the thickness at certain equidistant points will exactly correspond in thickness with the successive space-blanks. The distance between the centers of the different compartments of the space-rack 504 corresponds 35 with the distance between the points *x* on the space-bars. The particular space which is to be inserted is determined by the operation of what is termed a "space-selecting lever," which swings the space-rack so 40 that the appropriate opening in the rack is vertically over the opening in the line of type left when the space-bar is withdrawn. The space-selecting lever (indicated by 506 in Fig. 45 7) consists of an arm pivoted at the point 507 to a bracket 508, which is fastened to the justifying-slide 312. At the opposite end the space-selecting lever is provided with an adjusting-screw 509, adapted to engage with a stud 510 upon the side of the space-rack 504, as shown in Fig. 7, and a screw 509 serves the purpose of accurately adjusting the length of the lever 506, so that it will bring the space-rack 504 to the required distance to 55 bring the compartment containing the space-blanks of the proper thickness directly above the line of type in the line-holder. As the space-selecting lever is carried upon the same slide which actuates the space-bar driver 325, it will be obvious that the space-rack 504 will 60 be moved forward by the lever 506 according to the distance which the foremost space-bar is driven into the line-holder by the driver 325,

and the length of the lever 506 is so adjusted that when any given space-bar is driven in to such a point that when removed a given 70 size of space will exactly fill up the space left by the space-bar the compartment in the space-box 504 containing that particular size of space will be presented to the opening. Since it is infrequently the case that the space-bar 75 will be driven into the line exactly to a point which corresponds in thickness with one of the several space-blanks, it will be generally necessary to provide for the insertion of a space-blank of less thickness than the width 80 of the opening into which it is to be inserted, and means are therefore provided for causing the space-rack to return toward the left a sufficient distance to bring the channel containing such thinner space directly above the 85 line of type. The spaces are ejected from the space-rack 504 by means of the lever 511, carrying the space-ejector 530 at its loose end. At the other end it is pivoted at the point 513 to a post 514 on the bed-plate of the machine 90 and is held normally in a depressed position by means of a cord 515, Figs. 10 and 11, attached to a weight 516. The lever is held up by means of a cam 517 on the sleeve *o*. The connection between the lever 511 and 95 the cam 517 is effected by means of a roller 512, and the shape of the cam, as shown in Fig. 10, is such that its rotation first causes the lower beveled end of the ejector 512 to enter a short distance between the partitions 100 520 of the front of the space-rack in the proper compartment. Then the cam is so formed that for an instant the ejector rests in the position shown in Fig. 7 until a pin 518 on the face of the cam 339 raises the lever 506 and 105 swings it clear of the stud 510 on the space-rack 504, whereupon the weight 521, which controls the swing of the space-rack by means of the cord 522, moves it sufficiently to bring the flat surface of the space-ejector 512 110 in contact with the flat surface of the partitions 520 in the front plate 504 of the space-rack, whereupon the space-rack can swing no farther, and just at that instant the cam again beginning to curve the force of the 115 weight 516 draws down the lever 511, and the space-blank is pushed down into the line until its foot enters the opening above the space-bar, so as to prevent the types contiguous to the space-bar from closing up upon the withdrawal of the space-bar. The lever 511 is then held stationary in this position, owing to the fact that the curvature of the cam 517 remains constant for an appropriate portion 120 of its circumference until the space-bar has 125 been entirely withdrawn from the line, when it is allowed to complete its downward movement, forcing the space-blank entirely down into the line. The continued revolution of the cam 517 at once returns the lever 511 and 130 the space-ejector 512 to the former position. The space-blanks in the channels 500 of the space-rack are fed forward as required by gravity, assisted by weighted followers 519.

To prevent the space-rack from swinging too far from right to left, a bent arm 531 is attached to the space-box, passing through the upright plate 344. A hanger 532, pivoted at 5 533 to the upright plate 344, engages with the bent arm 531 and holds the space-box directly over the recess in the line-holder and prevents it being moved too far by the cord.

The bunter mechanism.—This will be best 10 understood by reference to Figs. 1, 11, and 12. In these sketches, *u* represents the galley upon which the type is discharged. 701 represents the line-bunter block, which is screwed to a slide 702, adapted to move longitudinally 15 in a suitable way 703 on the bed-plate. The bunter plate or plates 704 are screwed to the bunter-block 701 by means of the cap-plate and screws 705 and 706. In order to allow the ready changing of the width of the bunter- 20 plate 704 to correspond with the length of the line of type in the line-holder *c*, the plate 704 is composed of a series of separate plates of different widths, which may be taken out and removed from time to time, and thus fitted to 25 the width of the galley. They are preferably made of such individual widths that they may be combined to make any exact pica measurement up to the limit of the line-holder. The slide 702 and the bunter 704 are actuated 30 by means of the connecting-rod 707, the rear end of which is secured to a pin 708, arranged to slide in the slot 718, as shown in Fig. 11, and the front end of which is pivoted at the point 709 to the face of the disk 710 upon the 35 shaft *w*. The shaft *w* carries a collar 711, which is fastened to and rotates with it and contains on its periphery a series of gear-teeth 712. The mechanism for throwing the bunter in and out of operation is precisely 40 the same as is employed in Letters Patent of the United States No. 633,309, issued to C. W. Dickinson on the 19th day of September, 1899, and consists of a ring placed between the collar and the disk having an ear 45 or lug 713, with an opening containing a pin at one end and on the other a somewhat longer ear or lug, the shape of which is shown in Fig. 11 in the surface of the ring, which is formed in the manner shown in the afore- 50 said Letters Patent and is provided on either side with two channels adapted to hold or receive the two ears or lugs of the ring. Two spiral springs are provided on either side of the ear or lug, the effect of which is to keep 55 the ring constantly pressed against the collar which rotates with the shaft. The disk rotates loosely on the shaft *w* and is held in position by a circular disk and the screw which screws into the head of the shaft, and it will 60 be obvious from an inspection of the drawings in the present case, as well as from those attached to the aforesaid Letters Patent to C. W. Dickinson, that as long as the ring is in engagement with the teeth upon the face 65 of the collar the ring will rotate with the shaft and a reciprocating motion will be imparted to the slide 702. In order to throw the

ring out of engagement with the teeth on the collar 711 and to stop the rotation of the ring, a retaining-pawl 713 is provided, (shown in 70 Figs. 1 and 11,) attached to the short arm 714 of a lever pivoted at the point 715. This pawl is held in its normal position out of engagement with the teeth on the collar 711, and the lever 714 and the pawl 713 are retained 75 in their normal position, as shown in Fig. 1, by means of a light spring 716, passing under the shaft *w*, except at such times as the line-holder in its forward movement engages the free end of the lever 717, throwing it forward, 80 and thereby throwing the retaining-pawl 713 on the short arm of the lever clear of the ear of the ring, which immediately is thrown into engagement by the spring 716 with one of the teeth, thereby causing the ring to rotate with 85 the shaft, moving the bunter through the opening in the line-holder, and thereby pushing the line of type from the line-holder off onto the galley *u*. In its return movement the bunter is carried back clear of the upper rail 90 24 of the line-holder *c*, which is then free to drop at once by gravity to the lower or return track. In order to avoid accidents to the operator or mechanism, which might occur if the movement of the bunter was rigidly positive, 95 the pin 708 instead of being actually attached to the slide 702 is arranged to slide horizontally in a slot 718 in the slide, and its movement is controlled by the spring 719, attached at the point 720 to the slide 702 at the end of 100 the slot. This is attached, by means of a pin 720, to the slot at any convenient point. The effect of this construction is that by reason of the tension of the spring 719 the pin is normally kept against the rear end of the slot, 105 the tension of the spring being sufficient to insure a normal forward movement of the bunter; but in case of an unusual obstruction thereto it will yield, and thus avoid breakage or other injury.

The line-holder-returning mechanism.—The mechanism for automatically returning the empty line-holder along the lower track or way *d* is an improvement upon the mechanism described and claimed in Letters Patent of the United States No. 635,866, granted to me upon the 31st day of October, 1899. In the present patent, as will be seen by reference to Figs. 1, 4, and 12, this consists of an endless chain or belt 800, which passes around 115 a plain pulley 801 at the lower end and a sprocket-wheel 802 at the upper end, and its upper portion runs in the groove or channel 819 in the lower track *d*. The link chain 800 is provided with projecting lugs 804, secured 120 to it at suitable intervals, one of which lugs will engage the line-holder in the manner shown by the dotted line in Fig. 12 as soon as it drops to the lower track *d*. The link chain 800 is kept in continuous motion in the 125 direction of the arrows by means of the gear-wheels 805 and 806, which are connected with the main driving-shaft. The line-holder elevator consists of a shelf 807, attached to a

plate 808 by means of the screws 823, which plate slides up and down in a suitable way 803 in the side plate *f*, in which it is adapted to be moved up and down a limited distance. 5 In its upper position, as shown in the drawings, it forms practically a continuation of the upper track or way *b*, while in its lower position (shown by the dotted lines in Fig. 12) it forms a continuation of the lower or return 10 track or way *d*. It is normally held in its upper position by means of a weight 809, attached to the forked lever 810 812 813, pivoted at the point 811 to the side plate *f*. The forked lever 810 is composed at its upper end 15 of two Y-shaped forks 812 and 813, the former of which, 812, is connected, by means of a connecting-rod 822 by means of the screws 814 and 815, to the slide 808, as shown in Fig. 12. The weight 809 has a slot passing through its 20 head, through which the extremity of the lever 810 slides, and it may be adjusted and held in any desired position upon the end of the lever 810 by means of a screw 816, passing through the side walls into the slot. As 25 the line-holder *c* is moved upward on the way *d* by means of the lug 804 on the link chain 800 it comes in contact with a pin 817 upon the curved end of the lever 813. When the lever 813 by the action of the line-holder 30 reaches the point shown by the dotted lines in Fig. 12, the table 807 will have been lowered a sufficient distance to receive the line-holder *c*, which will pass over the extremity of the stud 817 onto the table 807. The lever 35 813 and the slide 808 will be held in the position shown by the dotted lines while the line-holder is passing over the top of the stud 817 on the free arm of the lever 813 and onto the table 807. As soon as the advancing line-holder is clear 40 of the rear end of the upper plate *a* it will be free to rise, and the force of the weight 809 will operate to immediately return the lever 810 to its normal position, thus raising the table 807 to its original position, with the front 45 end of the line-holder directly under the type-chute *s* in position to receive the type of the next line.

Should the line-holder elevator 807, with the empty line-holder, be released and begin to move up before the second line-holder has been entirely filled and started down on the upper track to the justifying mechanism, the slide 159, which is then in its normal position in the groove *g*, will engage the upper end of 50 the table 807 and prevent it from rising sufficiently to cause the rising line-holder to impinge against the line-holder being filled with the type and space-bars, which would be undesirable on account of increasing frictional 55 resistance to its movement along the upper track during the progress of the operation. The instant that the line-holder which has been filled is caused to move down its track *b* by reason of the action of the hooked slide 60 65 the table 807 is free to rise, and it will immediately carry the empty line-holder up to the proper position ready for refilling.

The front part of the plate *a* where the opening is made for the line-holder *c* to drop on the track 819 is beveled or cutaway, as clearly 70 shown by the dotted line 270 in Fig. 5. This is in order that the line-holder *c* if it drops directly in front of one of the lugs 804 on the chain 800 and is carried immediately upward before it quite rests on the track 819 may not 75 be caught by the front of the plate *a*.

Space-bar-returning mechanism.—In Patent No. 635,866, issued to me on the 31st day of October, 1899, in which a similar series of space-bars was shown, the space-bars 80 when withdrawn from the line were allowed to drop directly down through an opening into the raceway or channel *m* between the convolutions of an open coil of spring-wire, which was kept in continuous revolution by 85 suitable gear-wheels. The construction is very similar in the present machine. The rotating shaft *w* carries a gear-wheel 900, Figs. 1 and 11, which engages with a gear-wheel 901, mounted on a separate shaft 902, carrying 90 a sleeve 904, (shown in Fig. 12,) provided with an open coil 905, by means of which the space-bars are carried up to the storage end of the raceway *m*, to be inserted again into the line-holder. 95

It was found that in cases where the line-holder descended quickly or where space-bars were removed from very short words the succeeding space-bar would come in contact with and impinge against the former space-bar, 100 and thereby, by reason of the friction existing between the two, prevent the former from dropping into the raceway, and thus block the operation of the machine. In the present machine an opening 906 is provided in the top 105 plate, Figs. 8 and 22, just in front of the position of the foremost space-bar when it is withdrawn from the line-holder. A plate 910, secured to the sliding rods 908, sliding in a fixed block 907 on the bed-plate *i*, is provided, which 110 is adapted to be held in the positions shown in Figs. 2 and 22 by the springs 909 and 909. The rear face of this plate is in line with the stop 375 on the lower end of the top plate and the rear end of the slotted opening 13 in the 115 plate *f*, as shown in Figs. 3 and 22, thus preventing the rear end of the space-bar from swinging over toward the front before it is entirely withdrawn. In order to open and close the opening 906 by means of the sliding plate 910, 120 a pivoted lever 911 is provided, pivoted at the point 912 to the top plate *i*, one end of which is attached at the point 913 to the plate 915, which slides in an opening in the block 907. A roller 916 is provided on the free or outer 125 end of the lever 911, adapted to be engaged by a convex plate 372, formed upon the periphery of the disk 150, as shown in Figs. 2 and 3. This convex plate is so located that it extends the periphery of the disk 150 to very nearly 130 half of its circumference, and while the roller 916 is rolling over the rim 372 the opening 906 will remain open. The rim 372 on the periphery of the disk 150 is so located that it will

cause the forward movement of the plate immediately after a space-bar has been fully withdrawn and will retain it in such open position until the space-bar has dropped down 5 into the raceway *m* and until the beginning of the withdrawal of the succeeding space-bar. It will be obvious from Fig. 2 that when the roller 916 passes off the rim 372 the opening will be immediately closed by the action of the 10 springs 909 upon the plate 907. The operation of moving the space-bars up to the raceway *m* to the place of storage at the upper end is accomplished in the same manner as is shown in the aforesaid Letters Patent by 15 means of the spiral spring 905, attached to and rotated in a cylindrical space 904 by the gear-wheel 901. The opening 906 in the front of the top plate *i* extends a short distance back from where the space-bars drop down into the 20 spring 905. This part of the opening is covered by a thin plate 380, fastened by the screws 381. The space thus formed prevents the space-bars from jamming if they start upward before reaching the bottom of the raceway *m*. 25 *The driving mechanism.*—This is effected by means of a horizontal driving-shaft *t*, rotated from any convenient source of power. The space-bar-inserting mechanism, the space-bar-elevating mechanism, and the line-holder-returning mechanism are all actuated by devices attached to this shaft. The remaining mechanisms are actuated from the so-called "justifying-shaft" *w*, which in turn is actuated by the shaft *t*. The shaft *t*, driven 30 by means of the pulley *g* from a suitable belt, Fig. 1, is supported in bearings 39 and 40, respectively, on the side plate *f* and the frame-plate *h*, Fig. 4. The shaft *t* carries a collar 30, attached to it by the pin 41, to which a 35 screw-worm 31 is attached.

The shaft *w* rotates in two bearings 45 and 46 on the bed-plate *a*, as shown in Fig. 1. It carries at its upper end a cog-wheel 37, the teeth 38 of which engage with the teeth 33 of an idler 32 on idle shaft 36, rotating in a bearing 43, attached to the under face of the plate *a*. This shaft 36 carries on its extremity a worm-wheel 34, the teeth 35 of which mesh into the worm 31, mounted on the collar 30, fastened by the pin 41 to the driving-shaft *t*. When the driving-shaft *t* is rotated in the direction of the arrows, its motion will be imparted through the idle shaft 36 to the justifying-shaft *w*, the diameters of the various 45 50 55 gear-wheels being such that the speed of the shaft *t* is properly graduated so as to drive the shaft *w* at an appropriate rate of speed.

The justifying-shaft carries a sleeve *o*, by means of which the various mechanisms actuated by it are set in motion, as heretofore described.

Line-indicating mechanism.—In order to indicate to the operator when the line-holder is nearly filled with type and space-bars, so 60 65 that he may stop the composition at the end of a word or syllable, a bell mechanism of any convenient construction can be used. In

the present machine the bell 250 is secured by means of the bracket 251 to the line-holder guide-bracket by screws 252, which pass through slotted holes 253. This construction allows the bell to be adjusted longitudinally, so that it will ring at a greater or less distance from the end of the line, as may be desired by the operator. The lever 260 is pivoted at the point 254 to the bell-supporting bracket and has a hammer 255 on one end, while the free end is adapted to be engaged by a stop-block 6 in the line-holder as it is moved along during the progress of the composition. This engagement draws the hammer 255 away from the bell 250 against the tension of the spring 256. When the line-holder has advanced a sufficient distance for the block 6 to clear the end of the lever 260, 70 75 80 85 90 the spring 256 pulls it quickly over, causing the hammer to strike the bell 250. In order that the operator may at all times see how the composition is progressing, a graduated scale 258 is provided on the edge of the track-plate *f*. This scale may be graduated to any convenient unit, preferably in picas and fractions thereof. The end of the line-holder as it moves along down its track will clearly show to the operator just how many units of type 95 have been set in the line-holder at any time. A movable pointer 259 may be set at the graduation on the scale which corresponds with the length of the line for which the line-holder may be set. 100

The method of operation is as follows: The type characters are inserted one by one into the line-holder from the type-setting mechanism by gravity, the appropriate character being released by the operation of the keys V R 105 CX, &c., Fig. 1, by the finger of the operator. The character thus released falls through the chute *s* into the line-holder *c* and is immediately pushed forward in the line-holder against the next preceding character by the 110 cam 3, which also serves to advance the line-holder on the track *b* a distance equal to the thickness of the character inserted, thus leaving a space in the line-holder under the chute *s*, into which the next character can 115 be inserted. As soon as a complete word has been set the operator touches the key *p*, thus tripping the lever 138, whereupon a space-bar is first raised into the appropriate position by the space-bar-elevating mechanism and is immediately thereafter inserted into the line. When the line-holder *c* is completely filled, the line-holder is moved down to an appropriate point on its track opposite to the justifying-bar. Here it is intercepted by the foremost space-bar engaging suitable stops, which also throws the justifying mechanism into gear, whereupon the space-bars are driven in to expand the line and then removed and replaced by ordinary spaces. 125 130 When the line-holder is thus arrested in front of the justifying-bar and the justifying mechanism put in gear, the vertical plate 313, which is fixed permanently to the slide 313, comes

forward, engages with the end of the foremost space-bar, and drives it in. The extremities of the other space-bars are engaged by the front face of the pivoted plate 315 on 5 the slide 313, which plate will thus drive in the space-bars. As this plate is fastened by the pivot at the foremost end and held forward by a spring at the other end, it will not act upon the rear bars as vigorously as upon 10 the front bars, and its effect upon the space-bars will thus be to drive in the second space-bar a certain distance somewhat less than the first space-bar and drive in the third space-bar a slightly less distance than the 15 second and drive in the fourth space-bar a still slightly less distance than the third, and so on until all the space-bars have been driven in. In lines of considerable length the plate 315 may cease to come in contact 20 with the space-bars at all, as shown in Fig. 3, and they will be acted on by the bar 325 only. In this way the first space-bar will be driven in as far as it will go, and the space-bars from the second up to and including, say, the fifth 25 space-bar will be driven in each a little less distance than the one preceding it. After the removal of the first space-bar and the insertion of a suitable space in lieu thereof the line-holder will move farther down its track 30 and the second space-bar will be driven in as far as it will go and will then be removed and replaced by a space-blank, which operation will be repeated until all of the space-bars have been removed and replaced by space-blanks. When the space-bar driver operates to 35 drive in several of the space-bars, it is evident that if they were driven a uniform distance by a fixed bar parallel to the line of type they would not be driven as tightly as when the 40 driver later was acting on a less number. On this account it is necessary to provide that the space-bars toward the end of the line shall be driven in the first instance a less distance in order that as the pressure on the individual 45 space-bars is increased by the uniform pressure acting on a less number the space-bars may be eventually only driven substantially the same average distance through the line. In this manner uniformity of spacing is effect- 50 ed and the occurrence of large gaps or spaces at any one end of the line is avoided and the symmetry in appearance of the line is pre- 55 served. After the justifying is effected the line-holder is released and moves automatically to a point opposite to the galley, where the bunting mechanism removes it to the former in the same general manner as in earlier machines invented by me.

I claim as my invention—

60 1. The combination of a sliding plate, arranged to slide vertically in suitable ways, in the end plate; space-bar-elevating plate attached to and sliding vertically with the same; a spring attached at one end to the end plate, 65 and at the other to the sliding plate, whereby the latter is normally held in a raised position; a bent lever attached at one end to the

sliding plate, and pivoted at the other end to the frame; and means substantially as described, for intermittently actuating the lever 70 and drawing down the plate.

2. The combination of a sliding plate arranged to slide vertically in suitable ways in the end plate; space-bar-elevating plate, attached to and sliding vertically with the same; a spring attached at one end to the end plate and at the other to the sliding plate, whereby the latter is normally held in a raised position; a lever attached at one end to the sliding plate and pivoted at the other end to the 80 bed-plate; an arm carried on the lever, carrying a roller; a disk mounted on a sleeve rotating loosely on the driving-shaft, carrying on its surface a cam-groove in which the said roller travels; and means substantially as described, for causing the sleeve and the disk to rotate with the driving-shaft. 85

3. The combination of a sliding plate arranged to slide horizontally in suitable ways on the end plate; a sliding space-bar driver 90 attached thereto at one end; a bent lever pivoted to the frame attached thereto at the other end; a spring attached at one end to the bent lever and at the other end to the bed-plate, whereby the sliding plate is normally held in 95 an advanced position; a roller on the shorter end of the lever; a cam on the driving-shaft on the periphery of which the roller slides; and means substantially as described, for disengaging the connection between the cam 100 and the driving-shaft, whereby the space-bar driver may be actuated at the proper time with respect to the space-bar-elevating mechanism.

4. The combination of a plate arranged to 105 slide horizontally on the end plate; a sliding space-bar driver attached thereto at one end; a bent lever pivoted to the frame-plate, attached at one end to the sliding plate; a spring connected at one end with the bent lever and 110 at the other end to the frame-plate, whereby the sliding plate is constantly kept in an advanced position; a roller on the shorter end of the lever; a cam on the driving-shaft on the periphery of which the roller slides; and 115 means substantially as described, for disengaging the connection between the cam and the driving-shaft, whereby the space-bar driver may be actuated at the proper time 120 with respect to the space-bar-elevating mechanism.

5. The combination with the bed-plate of the machine, of a movable end plate, a space-bar-elevating slide, a space-bar-inserting slide, and devices for adjusting the end plate 125 with reference to the bed-plate, substantially as described.

6. The combination with the bed-plate of the machine, of a movable end plate attached to an arm moving in a suitable way in the 130 bed-plate, a space-bar-elevating slide and a space-bar-inserting slide, both actuated by suitable mechanism; and adjusting-screws at either end for adjusting the end plate with

reference to the bed-plate, substantially as described.

7. The combination of a sliding plate, arranged to slide vertically in suitable ways in the end plate; an elevating-plate attached to and sliding vertically with the same; a spring attached at one end to the bed-plate and at the other to the sliding plate, whereby the latter is normally held in a raised position; a bent lever attached at one end to the sliding plate, and pivoted at the other end to the frame; a sliding plate arranged to slide horizontally in suitable ways on the bed-plate; a sliding space-bar driver attached thereto at one end, a bent lever pivoted to the frame attached thereto at the other end; a spring attached at one end to the bent lever, and at the other end to the bed-plate, whereby the sliding plate is normally held in an advanced position; a loose collar rotating on the driving-shaft; a disk mounted on the collar, and rotating therewith, provided on its surface with a cam-groove; an arm attached to the actuating-lever of the elevating mechanism; a roller, carried on said arm actuated by the movement of the cam in the disk; a cam on the other end of said sleeve; a roller on the shorter end of the space-bar-driving lever, actuated by the movement of said cam; a cog-wheel attached to a driving-shaft; a dog upon the face of the rotating disk arranged to engage the cog-wheel, and cause the disk in the cam to rotate when the dog is released; a pivoted lever engaging the tail of the dog; a spring for throwing the dog into engagement when the pivoted lever is released, and a key mechanism for tripping the pivoted lever at the proper instant; a spring for restoring the same, and a spring-brake impinging against the periphery of the disk for retarding the movement of the same at the proper instant, the relation of the various elements being so timed to each other that the space-bar-driving mechanism operates at the proper instant.

8. A tapering wedged-shaped space-bar, slotted substantially throughout its length, and indented upon its lower surface for a certain distance to a certain extent, and for a short distance at the inner end to a less extent.

9. The combination with the line-holder and space-bars, of an adjustable brush arranged to be adjusted toward and from the line-holder, the bristles of which engage with the rear ends of the space-bars after insertion in the line-holder and prevent them from shifting from their normal position at right angles to the line of type.

10. The combination with the line-holder of a beveled plate arranged to engage with a slot upon its face; spring devices for throwing the plate constantly forward so as to hold the line-holder, and retard its downward motion; and adjusting devices for controlling the pressure upon the plate, substantially as described.

11. The combination with the line-holder of a vertical plate beveled at the rear end as shown; a rod upon which the same slides horizontally in the bed-plate at right angles to the line-holder; a spring at the end of the rod for throwing the same constantly forward and a thumb-screw whereby the tension upon the spring may be controlled. 70 75

12. The combination of a line-holder for receiving and containing a line of type having a fixed end wall and an adjustable line-stop which may be fixed at any desired point, and provided with a longitudinal opening 80 through its side wall, and having a slot cut in its front face so as to permit it to slide upon the projecting head of the reciprocating line-bunter.

13. The combination of a line-holder for receiving and holding a line of type having a fixed end wall and an adjustable line-stop which may be fixed at any desired point, and provided with a longitudinal opening through 85 its side wall, and a rib extending longitudinally along such longitudinal opening, and having a slot cut in its front face so as to permit it to slide upon the projecting head of the reciprocating line-bunter. 90

14. The combination of a traveling line-holder adapted to receive a line of type and temporary space-bars and having suitable stops to limit the length of the line; means for assembling types therein; a rapidly-revolving cam for advancing the individual types as fast as they are assembled; and mechanism for inserting space-bars into the line which is so timed as to always operate in unison with said cam, whereby the space-bars will always be made to enter the line without 105 striking either the types or the cam. 95

15. The combination of a vertical frame-plate; a traveling line-holder moving thereon upon a suitable track; a rapidly-rotating cam for advancing the individual types as fast as 110 they are assembled thereby causing the line-holder to move downward on the track; a shaft rotating in bearings in a movable plate to which said cam is attached; gear-wheels whereby the rotation of the main shaft is im- 115 parted at an accelerated speed to the cam-shaft, and devices for adjusting the position of the plate and the cam mechanism, in relation to the type-chute. 120

16. The combination of a vertical frame-plate; a traveling line-holder; an upper track on the frame-plate on which the line-holder travels in one direction; a return track or way below and parallel with the first track, upon which the line-holder travels in the opposite direction; a slide adapted to move along a groove in the frame-plate, and having a hook thereon, adapted to engage the line-holder; a cord and weight for causing the downward movement of said slide, and means 125 for returning the slide and weight to their upper normal position. 130

17. The combination of a frame-plate; a traveling line-holder; an upper track on the

- frame-plate, upon which the line-holder travels in one direction; a return track or way below and parallel with the first track, upon which the line-holder travels in the opposite direction; a slide adapted to move along a groove in the frame-plate, and having a hook thereon adapted to engage the line-holder; a cord attached to said plate having one weight permanently secured thereto; a second weight resting on the first; a stop adapted to arrest the descent of the second weight, at a suitable point, thereby preventing its further action in drawing down the slide; and means for returning the slide and weights to their upper normal position.
18. The combination of a frame-plate; a line-holder arranged to travel upon an upper track on the frame-plate in one direction, a return track or way below and parallel with the first track upon which the line-holder travels in the opposite direction; a slide adapted to move along the groove in the frame-plate; devices substantially as described connected therewith, whereby the slide is caused to engage with and move the line-holder; a cord attached to said slide, having one weight permanently secured thereto, a second weight resting on the first, a stop adapted to arrest the descent of the second weight at the suitable point, thereby preventing its further action in drawing down the slide; a second cord attached at one end to said slide; a grooved pulley to which the other end of said cord is attached; a grooved cam carried on the face of the pulley; a cord attached to the point of the cam arranged to be wound up by the movement thereof; a compressed-air chamber, the piston of which is connected with the cord attached to the cam; a key-lever for actuating the valve of the compressed-air cylinder; a spring device actuated by the key-lever for holding the valve of the air-chamber open, and a tripping device actuated by the slide for closing the valve at the proper instant.
19. The combination with the opening in the bed-plate, through which the space-bars drop into the returning-channel; of a movable cover; and devices actuated automatically from the justifying-shaft, which open and close the cover at the proper instant.
20. The combination with the opening in the bed-plate, through which the space-bars drop into the returning-channel; of a sliding plate arranged to close the same; springs for keeping the same normally closed, and a pivoted lever arranged to be actuated by a suitable cam on the justifying-shaft, for opening the same at the proper instant.
21. The combination of a plate sliding in suitable ways upon the side plate; a plate attached thereto onto which the line-holder is advanced; a forked lever pivoted to the side plate; a weight carried on the lower end of the lever; a link connecting the shorter fork of the lever with the sliding plate, a pin on the side of the longer fork of the lever on and projecting into the path of the line-holder, and a suitable endless-chain mechanism which advances the line-holder, whereby when the line-holder impinges against the pin, the plate is moved downward, and the weight raised and the line-holder permitted to pass from the lower way onto the plate and when the line-holder has passed the pin the plate and line-holder are raised by the force of the weight.
22. The combination of temporary spreading spacing devices inserted between types in a line; means for driving the foremost spacing device its full distance into the line and for causing all except said foremost spacing device, to be progressively driven in to spread the line; and means for thereafter replacing said spacing devices with ordinary spaces.
23. The combination of means for inserting temporary spreading spacing devices between types as they are assembled in line; means for driving the foremost spacing device its full distance into the line and for causing all except said foremost spacing device, to be progressively driven in to spread the line; means for limiting the amount of expansion; and means for replacing said spacing devices with ordinary spaces.
24. The combination of means for inserting temporary spreading spacing devices between types as they are assembled in line; means for driving the foremost spacing device its full distance into the line and for causing all except said foremost spacing device, to be progressively driven in to spread the line; means for replacing the spacing devices with space-blanks; means for delivering the line thus justified onto a galley.
25. The combination of means for inserting temporary spacing devices in a line of type while being assembled between confining walls; means for causing said spacing devices to be progressively advanced through the line such a distance that each successive space-bar shall eventually be advanced substantially the same distance; means for replacing said spacing devices with space-blanks, and means for removing the line thus justified onto a galley.
26. The combination of a line-holder for holding and limiting the length of a line of type; wedge-shaped space-bars for expanding the line; means for progressively driving in the space-bars to substantially the same final position so as to expand the line to the limit of the line-holder; and means for removing the space-bars successively and replacing them with ordinary spaces.
27. The combination of a suitable holder for holding and limiting the length of a line of type; means whereby wedge-shaped or tapering space-bars instead of ordinary spaces, are inserted between the words during the operation of assembling the line in the line-holder; means for driving the foremost spacing device its full distance into the line and for causing all except said foremost spacing device, to be progressively driven in to spread

the line; and means for removing the space-bars successively and replacing them with ordinary spaces.

28. The combination of the line-holder; the 5 wedge-shaped or tapering space-bars inserted therein; means for driving the foremost space-bar its full distance into the line and for causing all except said foremost space-bar, to be progressively driven in to spread the line; 10 and means for successively withdrawing the space-bars from the line.

29. The combination of a holder for holding and limiting the length of a line of type; means whereby wedge-shaped or tapering space-bars 15 are inserted into the line between the words during the operation of assembling in the line-holder; means for progressively driving in the space-bars so as to expand the line to fill out the line-holder; means for successively 20 removing the space-bars; means for inserting in the line of type, instead of the space-bars as each is removed, ordinary spaces of a thickness equal to or next less than the thickness of a space-bar which has been last removed, 25 at the point where it entered the line; and means for driving in the foremost remaining space-bar in advance of the others such a distance as will properly apportion the excess of fractional spacing throughout the line 30 whenever a space has been inserted of less than proper thickness.

30. The combination of a line-holder for holding and limiting the length of a line of type; means whereby wedge-shaped or tapering space-bars are inserted into the line between the words during the operation of assembling in the line-holder; means for progressively driving in the space-bars so as to expand the line to fill out the line-holder; 40 means for successively removing space-bars; means for inserting in the line of type, instead of the space-bars as each is removed, ordinary spaces of a thickness equal to or next less than the thickness of the space-bar which has been last removed, at the point where it enters the line; and means for driving in the foremost remaining space-bar in advance of the others, such a distance as will properly apportion the excess fractional spacing 45 throughout the line, whenever a space has been inserted of less than proper thickness, and for repeating this operation until the entire line is justified.

31. The combination of a suitable line-holder for holding and limiting the length of a line of type; means whereby wedge-shaped or tapering space-bars are inserted into the line between the words during the operation of assembling in the line-holder; means for 55 progressively driving in the space-bars so as to expand the line to fill out the line-holder; means for successively removing the space-bars; means for inserting in the line of type, instead of the space-bars as each is removed, ordinary spaces equal to or next less in thickness than the thickness of the space-bar which has been last removed, at the point at which it

had entered the line; means for driving in the foremost remaining space-bar in advance of the others such a distance as will properly apportion the excess fractional spacing throughout the line, whenever a space has been inserted of less thickness than the thickness of the removed space-bar at the point at which said space-bar entered the line, and for repeating this operation until the entire line is justified; and means for removing the justified line from the line-holder and delivering it upon a suitable galley.

32. The combination of a line-holder, traveling on a suitable track or way, containing the line of type in which wedge-shaped or tapering space-bars are inserted; a primary space-bar driver having a projecting shoulder adapted to drive in the foremost space-bar in 80 the line; a secondary space-bar driver, connected therewith; suitable spring devices whereby the force exerted by the secondary space-bar driver upon the ends of the space-bars may be regulated, and means for actuating both space-bar drivers at the same time, substantially as described.

33. The combination of a line-holder, traveling on a suitable track or way, containing the line of type in which wedge-shaped or tapering space-bars are inserted; a primary space-bar driver, having a projecting plate attached thereto arranged to drive in the foremost space-bar in the line; a secondary space-bar driver, composed of a plate pivoted 100 thereto; suitable spring devices whereby the force exerted by the secondary space-bar driver upon the ends of the space-bars may be regulated, and means for actuating both space-bar drivers at the same time, substantially as described.

34. The combination of a line-holder traveling on a suitable way or track, containing a line of type in which wedge-shaped or tapering space-bars are inserted; a slide moving 110 in suitable ways upon the bed-plate; the front face of which is substantially parallel with the ends of the space-bars; a supplemental plate attached to the side of the slide, and projecting beyond the front face of the 115 plate for driving in the former space-bar; a plate pivoted at one end of the slide, for the purpose of progressively driving in the space-bars, means substantially as described, whereby the force exerted by the plate on the ends 120 of the space-bars, may be regulated and means for actuating the mechanism, substantially as described.

35. The combination of a line-holder traveling on a suitable way or track, containing a 125 line of type in which wedge-shaped or tapering space-bars are inserted; a slide moving in suitable ways upon the bed-plate; a plate attached to said slide, the front face of which is substantially parallel with the ends of the 130 space-bars; a plate pivoted at one end of said plate, for the purpose of progressively driving in the space-bars, means substantially as described, whereby the force exerted by the

plate on the ends of the space-bars may be regulated; and means for actuating the mechanism, substantially as described.

36. The combination of a movable space-rack, divided longitudinally into compartments, containing spaces of the different sizes used; devices connected with the space-rack for bringing the compartment containing the space which is to be inserted in the line directly over the point at which it is to be inserted; a space-ejecting bar adapted to eject a single space from any one of the space-compartments, and to engage with the devices upon the space-rack, so as to produce the desired results; and means for actuating the space-ejecting bar.

37. The combination of a movable space-rack divided longitudinally into compartments containing spaces of the different sizes used; a slotted front plate on said space-rack having beveled partition-walls; a space-ejecting bar having its lower edge beveled and adapted to eject a single space from any one of the space-compartments, and means for actuating the space-ejecting bar.

38. The combination of a line-holder, traveling on a suitable track or way, containing the line of type in which wedge-shaped or tapering space-bars are inserted; a primary space-bar driver having a projecting shoulder adapted to drive in the foremost space-bar in the line; a secondary space-bar driver, connected therewith; suitable spring devices whereby the force exerted by the secondary space-bar driver upon the ends of the space-bars may be regulated; means for actuating the combined space-bar driver, substantially as described; means for successively removing the space-bars; a movable rack, divided longitudinally into compartments, containing spaces of the different sizes used; devices connected with the space-rack for bringing the compartment containing the space which is to be inserted in the line directly over the point at which it is to be inserted after the removal of each space-bar; a space-ejecting bar adapted to eject a single space from any one of the space-compartments, and to engage with the devices upon the space-rack, so as to produce the desired results; and means for actuating the space-ejecting bar.

39. The combination of a space-rack divided longitudinally into compartments containing spaces of the different sizes used; a slotted front plate on said space-rack having beveled partition-walls; a space-ejecting bar having its lower edge beveled; a pivoted space-selecting lever, adjustable longitudinally and secured to the space-bar-driving slide; means for throwing the free end of said lever out of engagement with the space-rack;

and means for causing the space-rack to reciprocate toward its normal position.

40. The combination of a movable space-rack, divided longitudinally into compartments each containing spaces of the different sizes used; a slotted front plate on said space-rack, having partition-walls beveled at the top; a space-ejecting bar arranged to slide between the partition-walls, having its opposite lower edge correspondingly beveled; a space-selecting lever pivoted to the justifier-slide adjustable longitudinally with respect to the space-rack; a stud on the justifying-shaft for throwing the free end of the lever out of engagement with the space-rack at the proper instant; a weight and cord whereby the space-rack is caused to reciprocate toward its normal position; a pivoted lever engaging with and actuating the space-ejecting bar; a cam on the justifying-shaft, and a weight connected with the lever for actuating the same at the proper instant.

41. The combination of a traveling line-holder adapted to receive a line of type and temporary space-bars, having a permanent end wall, and an adjustable line-stop to determine and limit the length of the line which may be fixed at any desired point; means for assembling types and temporary space-bars in said line-holder; and means for advancing the line-holder while the types are being assembled therein.

42. The combination with the bunter mechanism driven from the justifying-shaft of the machine; of a relieving device placed between the bunter and the actuating mechanism, for the purposes of relieving the strain upon the bunter when an obstruction is met with.

43. The combination with the bunter mechanism driven from the justifying-shaft of the machine; of a sliding bar arranged to slide in suitable ways on the bed-plate; a bent arm attached at one end to a sleeve on the actuating mechanism on the justifying-shaft and provided with a pin at the other end, arranged to slide in a slot in the slide; and a spring connected at one end with the bent arm and at the other end with the slides, whereby the bunter is caused to be actuated, except at such times as an obstruction is met with.

In testimony that I claim the foregoing as my invention I have signed my name, in presence of two witnesses, this 14th day of July, 1900.

FRANK McCLINTOCK.
